UNITED STATES PATENT OFFICE.

WALTER KIESER, OF CHARLOTTENBURG, GERMANY, ASSIGNOR TO GENERAL ELECTRIC COMPANY, A CORPORATION OF NEW YORK.

REGULATING MECHANISM FOR STEAM-TURBINES.

1,063,548.

Specification of Letters Patent.

Patented June 3, 1913.

Application filed February 7, 1912. Serial No. 676,048.

To all whom it may concern:

Be it known that I, WALTER KIESER, a citizen of Switzerland, residing at Charlottenburg, Germany, have invented certain new and useful Improvements in Regulating Mechanism for Steam-Turbines, of which the following is a specification.

This invention relates to elastic fluid turbines or engines, and its object is to provide an improved device whereby the admission valve controlling the flow of steam to the turbine is itself controlled by the pressure of the steam in that portion of the steam main between the valve and the turbine. Provision is made for taking care of slight variations in pressure and also of sudden variations, so that the admission valve is not subjected on the one hand to too frequent movements or on the other hand to violent movements.

The invention is illustrated diagrammatically in the accompanying drawing.

The admission valve 1 controls the flow of steam through the main 2 to the engine or turbine in the direction of the arrow. From a region between the valve and the turbine a pipe 3 leads to one side of a power piston or other movable abutment 4, the opposite side of which is exposed to atmospheric pressure. A spring 5 augments said atmospheric pressure and biases the piston to the right in the drawing. In line with the cylinder 6 in which the piston works is a fluid brake, comprising a piston 7 working in a cylinder 8, whose ends are connected by a passage 9 regulated by a bypass valve 10, whereby the flow of fluid from one end of the cylinder to the other can be more or less retarded as desired, and the movement of the piston 7 correspondingly controlled. The piston rod 11 passes out at each end of the cylinder 8, and at one end is attached to a spring 12 which is also connected to the rod 13 extending from the piston 4. The other end of the rod 11 enters a cylinder 14 where it is attached to a slide valve 15 which controls the flow of hydraulic pressure entering said cylinder through a pipe 16 and exhausting through the pipe 17. A duct 18 connects the two ends of this cylinder, and at the end opposite that through which the rod 11 enters a pipe 19 leads to a cylinder 20, which it enters above a piston 21. A spring 22 urges this piston upward, in opposition to the hydraulic pressure supplied

through the pipe 19. The rod 23 of this piston is connected to the valve 1.

A speed-responsive device 24 controls a pilot valve 25 which regulates the supply of fluid pressure to the upper end of the cylinder 20, above a piston 26 adapted to abut upon the piston 21 and actuate the same under certain conditions. A rod 27 connects the piston 26 with the floating lever 28 by means of which the speed responsive device actuates the pilot valve, constituting a follow-up device of well known character.

The method of operation is as follows:— The smaller movements of the piston 4 due to small variations in the steam pressure, are taken up by the springs 5 and 12, and the suddenly occurring impacts are absorbed by the fluid brake, so that only the average of the pressure variations occurring in the chamber 29 above the admission valve is transmitted to the valve-actuating piston 21. For example, if the steam pressure in the chamber 29 increases by a certain definite amount, then the power piston 4 is shifted against the tension of the spring 5 and this movement is transmitted through the fluid brake to the slide valve 15, which admits hydraulic pressure to the duct 18 and pipe 19 and so to the space between the pistons 21 and 26. The result is that the piston 21 is forced downwardly against the tension of the spring 22, and the valve 1 is partially closed to decrease the amount of steam admitted to the turbine, and thus prevents the increased steam pressure from augmenting the speed of the turbine. The pressure in the chamber 29 is also decreased by this partial closing of the valve 1, so that the spring 5 is enabled to return the piston 4 to its normal position, pulling with it the slide valve 15 and shutting off the hydraulic pressure from the cylinder 20. A similar action of these parts occurs, in the opposite direction, of course, when the steam pressure in the chamber 29 drops to any extent.

100

Any serious variation in the speed of the turbine acts to vary the position of the valve 1 through the speed responsive device 24, the pilot valve 25, and the upper piston 26 in the cylinder 20, which upon being forced down by the fluid pressure above it forces down in turn the piston 21 and thus tends to close the admission valve.

This invention is especially applicable to turbines driven by exhaust steam from other

110

engines or apparatus, but it may be of service also in connection with live steam machines where variable pressures are encountered.

5 I have disclosed certain novel features which are not claimed herein because they form part of the subject-matter of my pending application, Serial No. 631,678, filed June 7, 1911.

10 In accordance with the provisions of the patent statutes, I have described the principle of operation of my invention, together with the apparatus which I now consider to represent the best embodiment thereof; but 15 I desire to have it understood that the apparatus shown is only illustrative, and that the invention can be carried out by other means.

What I claim as new and desire to secure 20 by Letters Patent of the United States, is:—

1. The combination with an admission valve for an engine, of means for automatically regulating the same, consisting of a piston connected to said valve, a valve controlling a supply of fluid pressure to the piston, a movable abutment exposed to the 25

steam pressure in a region between the admission valve and the engine, and connections between the abutment and said controlling valve comprising means for taking up small variations in movement and means for opposing sudden movements. 30

2. The combination with an admission valve for an engine, of means for automatically regulating the same, consisting of a piston connected to said valve, a valve controlling a supply of fluid pressure to the piston, a movable abutment exposed to the steam pressure in a region between the admission valve and the engine, and connections between the abutment and said controlling valve comprising spring means for taking up small variations in movement and a fluid brake for opposing sudden movements. 35

40 In witness whereof, I have hereunto set my hand this 23 day of January, 1912.
